Fig. 2

Fig. 3

Fig. 4

Fig. 5

Fig. 6

Fig. 7

Fig. 8

Fig. 9

Fig. 10

Fig. 11

FIGURE 1 is a top plan view of a packaging tray, showing our new design;

FIGURE 2 is a side elevational view thereof;

FIGURE 3 is an end elevational view thereof;

FIGURE 4 is an enlarged fragmentary cross-sectional view taken on line 4-4 of FIG. 1;

FIGURE 5 is an enlarged fragmentary cross-sectional view taken on line 5-5 of FIG. 1;

FIGURE 6 is a top plan view of the packaging tray shown in FIG. 1, showing a modified form thereof wherein the upraised ridges thereof are provided with shallow, spaced depressions, being otherwise the same as FIG. 1;

FIGURE 7 is a side elevational view thereof;

FIGURE 8 is an end elevational view thereof;

FIGURE 9 is an enlarged fragmentary cross-sectional view taken on line 9-9 of FIG. 6;

FIGURE 10 is an enlarged fragmentary cross-sectional view taken on line 10-10 of FIG. 6; and

FIGURE 11 is an enlarged fragmentary cross-sec-

tional view taken on line 11-11 of FIG. 6.

The side and end views not shown are the same as the side and end views illustrated.

We claim:

The ornamental design for a packaging tray, substantially as shown and described.
